United States Patent [19]

Panas

[11] Patent Number: Des. 285,550

[45] Date of Patent: ** Sep. 9, 1986

[54] HIGH-VOLTAGE CONTROL MODULE

[75] Inventor: William R. Panas, Glenview, Ill.

[73] Assignee: S&C Electric Company, Chicago, Ill.

[**] Term: 14 Years

[21] Appl. No.: 465,713

[22] Filed: Feb. 11, 1983

[52] U.S. Cl. D13/24

[58] Field of Search D13/24, 26, 27, 28,
D13/29, 30, 40, 99; 337/6, 159, 186, 201

[57] CLAIM

The ornamental design for a high-voltage control module, substantially as shown and described.

DESCRIPTION

FIG. 1 is an isometric view of a high-voltage control module showing my new design;

FIG. 2 is a front elevational view thereof, the rear view being a mirror image;

FIG. 3 is a left side elevational view thereof;

FIG. 4 is a right side elevational view thereof.

FIG-1FIG-2FIG-3FIG-4
